M. N. RUSSELL

SHADE HOLDER

Filed May 14, 1923

FIG. 1.

Watson, Col. Morse & Grindell
Albion

UNITED STATES PATENT OFFICE.

MARK N. RUSSELL, OF SYRACUSE, NEW YORK, ASSIGNOR TO PASS & SEYMOUR, INC.,
OF SOLVAY, NEW YORK, A CORPORATION OF NEW YORK.

SHADE HOLDER.

Application filed May 14, 1923. Serial No. 638,981.

To all whom it may concern:

Be it known that I, MARK N. RUSSELL, a citizen of the United States, and a resident of Syracuse, in the county of Onondaga and State of New York, have invented certain new and useful Improvements in Shade Holders, of which the following is a specification.

The present invention relates to shade holders and particularly to devices for securing shades on electric fixtures.

The object of the invention is to produce a shade holder which is simple and inexpensive, and which is adapted to be securely connected to a lamp socket or other receptacle, and is also adapted to suspend a lamp shade without the use of the usual radial screws.

Another object is to produce a fixture of this character which presents a neat and more or less ornamental appearance.

The invention will be described in connection with the accompanying drawings, in which:—

Figure 1 is a side view of an electrical receptacle adapted to be connected to a wall or ceiling, the parts constituting the shade holder being shown in cross section.

Figure 2 shows the four individual parts of the shade holder separated and partly in section.

Figure 3 is a side view, partly in section, of a modified form of my invention.

Referring to the drawings 10 indicates a lamp base or receptacle of ordinary construction and consisting of porcelain or other insulating material. The particular base illustrated is adapted to be attached to a ceiling of a room, but it will be understood that the present invention is adapted to be used in connection with numerous other forms of receptacles or lamp sockets. As illustrated in the drawing, the receptacle 10 is formed with a neck 11 at the lower end of which is a rib or shoulder 12 surrounding the screw shell 13 of the lamp socket.

A split ring A is adapted to be sprung over the shoulder 12 onto the neck of the receptacle. This ring is provided with a shoulder 14, and a threaded portion 15 below the shoulder. The ring is of brass, or other elastic material, and is split as at 16. When in position the shoulder 14 of the ring rests on the shoulder 12 of the receptacle.

A second ring shaped member B is provided with a threaded cylindrical portion 17 adapted to be screwed onto the threaded portion 15 of the ring A. Member B is provided with an inwardly projecting annular flange 18 adapted to fit against the lower end 19 of the neck of the receptacle. When the ring member B is screwed onto the ring A tightly the shoulder 14 will be drawn down upon the shoulder 12 and the flange 18 will fit against the lower end of the neck of the receptacle, thus securing the parts together without any play or lost motion. When thus assembled a shade may be held in the member B by three or more screws 19, as shown in Figure 3. I prefer, however, to suspend the shade in the manner to be presently described and to dispense with the screws which are unsightly and more or less unreliable. The screws are also liable to crack the shade due to expansion when the lamp is in use.

Before screwing the part B onto the part A I preferably insert in the part B a threaded ring C provided with a flange 20 adapted to be clamped between the flange 18 and the lower end of the neck of the receptacle when the parts A and B are screwed together tightly.

On the outside of the threaded ring C is screwed a similar, but slightly larger, threaded ring D having a flange 21 at its lower end extending outward sufficiently to support a shade, such as shown at 22 in dotted lines, without the aid of the screws 19. As stated, the screws 19 are preferably omitted, but the skirt 23 of the member B is retained and is adapted to hide the several threaded members and produce an ornamental finish between the lamp base and the shade.

It will be noted that this improved shade holder is adapted to be connected to any lamp receptacle which is provided with an annular shoulder or equivalent supporting means at its lower or outer end. The parts are all of comparatively light material and inexpensive but, nevertheless, suspend the shade in a substantial manner and without danger of breakage. The skirt or canopy 23 preferably extends down to the normal position of the shade to give the fixture a proper finish when the parts are assembled. The ring D may be provided with small depend-

ing lugs 24 to facilitate turning it into place, the lugs being punched out of the metal of the flange 21.

Having described the invention what I claim and desire to secure by Letters Patent is:

1. The combination with a lamp receptacle having an external annular shoulder, of a screw ring having an internal annular shoulder, a second screw threaded member adapted to draw said shoulders together, said second member having an inturned annular flange adapted to engage the end of the receptacle, and means associated with said second member for supporting a shade.

2. The combination with a receptacle having a neck and an annular shoulder, of a threaded split ring provided with an internal shoulder adapted to engage the shoulder on the receptacle, a second threaded ring cooperating with the first named ring and having an internal flange, and a shade supporting ring having a flange adapted to be clamped against the outer end of the receptacle by said second member.

3. The combination with a receptacle having an annular rib surrounding its lamp receiving portion, two cooperating threaded members each provided with a flange or shoulder to engage the inner and outer surfaces of the rib, and a shade supporting member having a flange adapted to be clamped against the outer surface of the rib.

4. The combination with a lamp receptacle having an annular rib surrounding its lamp receiving portion, of a split ring having a threaded portion surrounding said rib and a shoulder to engage the rib, a member having a threaded portion to engage the split ring and a flange adapted to engage the outer part of the rib, a threaded ring having a flange adapted to be clamped between the flange of said member and the rib, and a second threaded ring adapted to be screwed onto said first threaded ring and having a shade supporting projection at its lower margin.

5. The combination with a lamp receptacle having an annular rib surrounding its lamp receiving portion, of a split ring having a threaded portion surrounding said rib and a shoulder to engage the rib, a member having a threaded portion to engage the split ring and a flange adapted to engage the outer part of the rib, a threaded ring having a flange adapted to be clamped between the flange of said member and the rib, and a second threaded ring adapted to be screwed onto said first threaded ring and having a shade supporting projection at its lower margin, said member engaging said split ring having a skirt or canopy surrounding and obscuring the several threaded members.

In testimony whereof hereunto affix signature.

MARK N. RUSSELL.
